APPARATUS FOR STORING AND DISPLAY- ING MAPS

Myron D. McCauley, Huntington Woods, Mich.

Application June 7, 1937, Serial No. 146,843

17 Claims. (Cl. 40—30)

The present invention relates to apparatus for storing maps and like display articles of roll form in a protective cabinet and for selectively unrolling the maps or display articles to extend them through an opening and above their storage compartment for the purpose of displaying the same to view. The apparatus is particularly designed for handling large maps, such as are used by municipalities, cities, governments, oil companies, public utilities, railroads, steamship companies, etc., and which ordinarily are of such great size and weight that moving them by hand is very difficult.

The primary object of the present invention is to provide a protective cabinet in which several roll maps or display articles may be stored or filed, the maps so stored or filed being protected from destruction by fire, water, dust or grime.

Another object of the invention is to provide a filing or storage cabinet of the character above referred to with electrically powered apparatus for selectively moving the map rolls into a position adjacent an opening therein whereby apparatus positioned above the same may be operated to unroll a selected map and extend it vertically so that it may be conveniently and closely inspected, and also for extending an unwound portion of the map in an angular position, similar to a drafting board position, where it may be inspected, checked, corrected or redesigned. As to this latter respect the member which is provided to normally close the opening through which an unwound map extends is adapted to be moved to an inclined position, similar to a drafting board position, so that work may be conveniently performed upon a portion of a map resting upon the same.

Another object of the present invention is to provide apparatus of the character above referred to embodying electrically powered means for rewinding an unrolled map upon its respective drum and in combination therewith a friction brake for retarding reverse movement of the map unwinding means in order that the rewound map will be wound in a fairly tight condition on its drum. The means for unwinding the map from a selected drum comprises an electrically powered roller mounted above the housing in which the several map supporting drums are contained and depending from the drum are straps which are adapted to be hooked on to the selected map to unwind it from its drum and to extend it vertically above the housing, and in some cases to wind the map upon the roller. During rewinding of the map upon its drum there is a tendency for

the unwinding roller to overrun the winding drum and to prevent such a condition friction means acts to retard movement of the roller in an unwinding direction.

Another object of the invention is to provide controls for the means for selectively positioning the drums in their operative position, said controls being so constructed whereby the means is manually placed in operation and is automatically stopped. That is, in selecting a map drum the operator manually holds the control in an operative position, and upon releasing the same so that it falls to its inoperative position, the drum moving means continues to operate until the next drum is placed in its operative position, at which time it automatically stops.

Another object of the present invention is to provide means for indicating, visibly, the relative position of the map drums with respect to the operative position. This means co-operates especially with respect to the above mentioned controls inasmuch as the operator may release the manual control upon indication that the drum next to the one desired has passed the operative position so that the automatic control will automatically stop the drum carrier with the selected drum in operative position.

Another object of the invention is to provide manual controls for the means for unwinding the maps from or rewinding the maps upon their drums, the controls including a foot operated friction clutch so that the operator may conveniently start and stop movement of a map when it is desired to inspect different portions thereof. In some cases the maps may be quite long, say fifty or a hundred feet, and in view of this condition the controls for moving the maps are provided with means for varying their speed of movement. This means enables the longer maps to be rapidly unwound from or wound upon their drums.

Another object of the present invention is to provide means for automatically stopping operation of the map unwinding means in order to prevent the maps from being torn from their drums.

With the above and other ends in view the invention is more fully disclosed with reference to the accompanying drawings, in which

Figure 1 is a front elevation;

Fig. 2 is a vertical, transverse section;

Fig. 3 is a vertical section through the housing, illustrating the operating mechanism in elevation;

Fig. 4 is a view taken at right angles to Fig. 3;

Fig. 5 is a horizontal section, illustrating a part of the controls and the indicator in plan;

Fig. 6 is an enlarged fragmental plan of a control device;

5 Fig. 7 is an end elevation corresponding with Fig. 6;

Fig. 8 is a side elevation corresponding with Fig. 6;

10 Figs. 9 and 10 are sections taken on lines 9—9 and 10—10 respectively, of Fig. 5;

15 Figs. 11 and 12 are sections illustrating safety controls for the map drums.

Fig. 13 is a fragmental perspective illustrating the map unwinding means;

15 Fig. 14 is a transverse section of the map unwinding roller, and

Fig. 15 is a fragmentary section of a detail.

Like characters of reference are employed throughout to designate corresponding parts.

20 The numeral 1 designates the vertical end members of a cabinet, the end members being united at their upper ends by a cross structure 2 and having a storage housing 3 between the lower ends thereof. The storage housing 3 comprises a rear vertical wall 4, a front vertical wall 5 and a removable cover 6. The front and rear walls, the cover 6, and also the bottom 7 are insulated at 8 to render the housing waterproof. The front wall of the housing has an opening in which a flat closure 10 is supported by a hinge 11. The closure 10 depends from the hinge 11 and has a roller 12 on its lowermost, horizontal edge. In one of its operative positions the roller 12 is supported in the position 35 shown in Fig. 2 by full lines, and in another operative position the roller is supported in the position shown in broken lines in Fig. 2. In the broken line position illustrated the closure 10 is held in an inclined position by a collapsible supporting structure 13. The inclined position of the closure is hereinafter termed the "drafting board" position.

Also hingedly mounted in the opening 9 is a closure element 14, which is adapted to be moved 45 to the position shown in broken lines (in Fig. 2) in order to permit access to the interior of the housing 3.

50 Mounted in the housing 3 is a movable support for a plurality of drums upon which maps or similar articles are wound. The support comprises two, vertically spaced, rotatable shafts 15 and 16 with sets of sprockets 17 and 18, respectively, thereon. Endless chains 19 are trained over the sprockets on the respective shafts, 55 the chains having special links 20 at regularly spaced intervals which constitute bearings for rotatably supporting drums 21. The drums 21 have maps 22 wound thereon. It is obvious that, by rotating one of the shafts 15 or 16, by 60 a suitable power means, the chains 19 will carry the drums 21 past the opening 9. The invention, as will hereinafter be described, provides means for so moving the chains 19 and means for controlling said moving means in order that any selected drum 21 may be placed in a position where 65 a map may be unwound therefrom and trained under the roller 12.

70 The means for moving the chains 19 comprises an electric motor 23, supported by a cross frame member 24 in one of the vertical end members 1, and connected through a gear reduction mechanism contained in the housing 25 to the shaft 15. The motor 23 is of the reversible type and when operated in either direction causes movement 75 of the chains 19.

The switch for controlling the motor 23 is of standard type and its details of construction are not, therefore, shown here. For an understanding of the invention, it is assumed that the switch generally designated 26 and shown as having 5 a control shaft 27, functions when the shaft 27 is moved rotatively in one direction to operate the motor 23 in one direction, and when the switch is operated in a reverse direction, to operate the motor in a reverse direction. When 10 the shaft 27 is in an intermediate position the switch is open and the motor 23 is inoperative.

The means for operating the switch 26 comprises a horizontal rod 28, co-axial with the shaft 27 and having a handle 29 disposed externally 15 of the end member 1 whereby the rod may be manually rotated. On the inner end of the rod 28 is secured a head 30 having two parallel pins 31 slidably mounted therein. The ends of the pins 31 are inclined, as indicated at 32 in Fig. 6, 20 and the pins are yieldably held with their inclined ends projected by coiled springs 33. Each pin 31 has a radial finger 34. Adjacent the head 30 is a bracket 35 carrying two cam surfaces 36, and when the head 30 is rotated, by manually 25 rotating the rod 27, the fingers 34 on respective pins are adapted to engage respective cams 36. That is, if the head 30 is rotated clockwise, the finger on one pin engages the adjacent cam surface 36 and functions to retract that pin, and 30 conversely, if the head 30 is rotated counter-clockwise, the finger on the other pin engages the other cam 36 and retracts said other pin.

Secured on the switch shaft 27, adjacent the head 30, is a collar 37 having a radial arm 38 normally disposed between the ends 32 of the pins 31. Therefore, when the head 30 is moved rotatively in one direction, one of the pins 31 carries the arm 38 and imparts rotation to the switch shaft 27 to operate the switch 26, whereas rotation of the head 30 in the other direction causes the other pin 31 to move the arm 38 in the other direction and causes rotative movement of the switch shaft 27 in the opposite direction. Movements of the shaft 27 in this manner operate the 45 switch 26 to operate the motor 23 in opposite directions. With the radial arm 38 vertical, as shown in Figs. 6, 7 and 8, the switch is in a neutral position and the motor 23 is inoperative.

50 Mounted upon the collar 37 is a second radial arm 39, the latter arm being disposed diametrically opposite with respect to the arm 38. That is, the arm 38 in its normal position, extends vertically above the collar 37, and the arm 39, under the same conditions, extends vertically 55 below the collar. Connected to the radial arm 39 is a depending link 40 having a pair of spaced collars 41 and 42 fixed thereon (see Figs. 2 and 4). A lever 43, mounted upon a rotatable shaft 44, has its swinging end normally held in yielding engagement with the collar 41 by a coiled spring 45 which is sleeved on the link 40 and supported by the collar 42. Also mounted upon the shaft 44 is a second lever 46 having a cam-like head 47 adapted to be engaged by axially 60 projecting elements 48, one of which is provided on each drum 22.

65 In the vertical end member 1, adjacent the control handle 29, is provided an opening 49. Mounted behind this opening, and having indicia 70 thereon adapted to be displayed through said opening, is a rotatable disk 50. The disk 50 is connected to the driven shaft 15 by a chain 51 and sprockets 52 whereby it rotates in unison therewith. As the shaft 15 is rotated and the 75

40. CARD, PICTURE, AND
SIGN EXHIBITING,

2,110,771

3

drums 22 are moved with the chains 19, the indicia on the disk 50 indicates which drum is in or which drums are near the operative position relative to the roller 12.

5 Each drum 22 has a friction disk 53a thereon, and when a selected drum is in the so-called operative position, mentioned above, the friction disk 53a thereon is in a position whereby it may be engaged by a driving disk 53. The driving disk 53 is rotated through gearing contained in the housing 54 by an electric motor 55. The electric motor is suspended by arms 56 which have a bearing 57 slidably mounted upon a trunnion shaft 58. A flexible arm 59 has a roller 160 10 upon its upper end engaging a bearing surface 161 on the arms 56 whereby swinging movement of the flexible arm 59 swings the motor 55 and housing 54 to move the disk 53 into contact with the properly positioned friction disk 53a. 15 The two disks 53 and 53a are thus related with their axes of rotation at right angles and when the periphery of the disk 53 engages the face of the disk 53a it imparts rotation thereto.

With a drive mechanism of the character above 20 described, that is, where the periphery of one disk engages the face of the other disk, the distance of such contact from the center of rotation determines the relative speed of rotation between the two disks. In the present case, by 25 sliding the bearing 57 on the trunnion shaft 58, the point of contact of the disk 53 on the disk 53a may be varied so that such contact takes place nearer or more remote from the center of the disk 53a. The proper relationship is maintained between the two disks 53 and 53a during 30 such adjustment movement by a bracket 159, secured to the motor and housing 54, and having an elongate slot therein into which the projecting element 48 on the aligned drum 22 is 35 adapted to engage, after the motor has been swung but a comparatively short distance upon its swinging support.

The means for swinging the flexible arm 59 to cause the above described swinging movement 40 of the motor 55, or in other words, engagement of the clutch parts 53 and 53a, comprises a rotatable shaft 61 having a foot pedal 62 thereon. Slidably splined upon the shaft 61 is a dog-tooth clutch part 63 adapted to engage a similar clutch 45 part 64 connected to the flexible arm 59 and providing a support therefor upon the shaft 61. The splined clutch part 63 may be moved into or out 50 of engagement with the clutch part 64 by a rocking lever 65 having a forked end 66 engaging a pin 67 on the clutch part 63.

Mounted for both sliding and rotary movement, adjacent the control rod 28, is a second control rod 68. Splined upon the control rod 68, and held against longitudinal movement by 55 a bracket 69 attached to the vertical end member 1, is a collar 70 having a parti-circumferential spiral groove 71. A pin 72 on the upper end of the rocking lever 65 extends into the groove 71 so that rotation of the collar rocks the lever. 60 A handle 172 is mounted on the outer end of the rod 68 for manually rotating the same.

From the description immediately foregoing it 65 becomes apparent that by rotating the rod 68 in the proper direction, the lever 65 will be rocked, and the clutch element 63 will be moved, from the inoperative position shown in Fig. 4, into engagement with the clutch element 64. Therefore, manually moving the foot pedal 62 rotates the shaft 61, the clutch parts 63 and 64, and 70 swings the flexible arm 59 whereby the clutch

disk 53 engages the disk 53a. When the manual pressure is removed, gravity causes disengagement of the disks 53 and 53a.

The relative speed of the two clutch parts 53 and 53a is also controlled by the rod 68, and comprises a collar 73, fixed upon the rod 68, and having a radial pin 74. A vertical shaft 75 has a radial lever 76 thereon with a forked end 77, and the pin 74 is moved, upon rotation of the rod 68 to engage the clutch disks 53 and 53a, to 10 engage the forked end of the lever 76. At its lower end, the vertical shaft 75 has a radially extending lever 78 with a forked end 79 engaging a pin 80 on the bearing 57. Upon the shaft 75 is a torsion spring 81 which tends to rotate 15 the shaft 75 to hold the bearing 57 in the position shown in Fig. 4, which is the low speed position. By manually pulling the rod 68 outwardly, rotation of the shaft 75 may be caused, and the lever 78 will shift the bearing 57 toward the left 20 hand side of Fig. 4. This movement shifts the point of contact of the disk 53 with the disk 53a nearer to the center of the disk 53a and increases the speed of rotation of the disk 53a.

Mounted in the cross structure 2 is a roll 82 25 having a friction disk 83 connected thereto. Adjacent the end of the roll 82 is a trunnion shaft 84 having a bearing 85 slidably and rotatably mounted thereon and supporting the arms 86. A motor 87, gear housing 88 and a friction disk 30 89, driven through gearing contained in the housing 88 by the motor 87, are pivotally supported upon the upper ends of the arms 86. A bracket 90 is connected to the gear housing and motor and has a slot 91 through which the end of a 35 projecting element 92 on the roll 82 extends.

To move the friction disk 89 into engagement with the friction disk 83, a flexible arm 93 is mounted to swing upon a trunnion 94, there being an arm 95 at right angles to the flexible arm 40 93 and a roller 96 upon the upper end of the flexible arm engaging a bearing surface 97 on the swinging arms 86. The right angular arm 95 is connected by a link 98 to a radial arm 99 45 on a clutch part 100 on the shaft 61. The clutch part 100 is adapted to be engaged by the splined clutch part 63 to connect the same whereby rotation of the shaft 61, caused by manual pressure on the pedal 62, pulls the link 98 downwardly and rocks the flexible arm 93 and causes engagement of the friction disks 83 and 89.

In order to vary the relative speed of the friction disks 83 and 89 a lever 101 is provided upon a vertical shaft 103, coaxial with the vertical shaft 75, and has a forked end engaging a pin 55 102 whereby swinging movement of the lever 101, resulting from rotative movement of the shaft 103, causes the motor 87 and housing 88 to shift axially of the trunnion 84, and the disk 89 to be moved nearer to the center of the disk 83. A 60 spring (not shown) similar to spring 81, normally holds the motor 87, the housing 88 and the friction disk 89 in the low speed position shown in Figs. 3 and 4. To rotate the vertical shaft 103 a lever 104 is mounted on its lower end and its 65 forked end 105 is adapted to be engaged by the pin 74 whereby sliding movement of the rod 73 will impart rotation thereto.

The springs which hold their respective friction disks in the low speed position have an additional 70 function. Referring again to the bracket 59, it will be noted that it is provided with a projecting portion 106 which engages a brake shoe 107, supported by a swinging arm 108, so that the pressure exerted by the spring 81 forces the shoe 75

into engagement with the periphery of the disk 53a. As will hereinafter appear, the brake shoe 107 also assists in positioning a selected drum 22 in the "operative position". The bracket 90 has 5 a similar projecting portion 109 acting upon the brake shoe 110 to force it into engagement with the periphery of the friction disk 83 under pressure of a torsion spring (not shown) similar to and functioning in the same manner as the 10 spring 81.

In co-axial alignment with the control rod 68 is a switch 111, the rod 68 having a sliding connection therewith as designated at 112. The switch 111 is of standard type and functions upon 15 rotation of the rod 68 and its operating shaft 113, through the connection 112, in one direction to set the motor 55 in operation, and in the other direction, to set the motor 87 in operation.

20 The roll 82 has a plurality of circumferentially extending grooves 114 in which flexible straps 115 are mounted, one of such grooves and straps being shown in Fig. 13. At their free ends, the several straps are united by a hook member 116, and 25 the roll 82 has a longitudinal groove 117 for the reception of the hook member when the straps are completely wound in their respective grooves. Each map 27 has a hook member 118 attached thereto and adapted to be connected to the hook 30 member 116 as shown in Fig. 13.

In each drum 21 is provided a screw 119, the screw being received in a screw-threaded bore in one of their axial supporting members 120. The special link 20, which receives the axial drum supporting member 120, has a plate 121 secured thereto and supporting a pin 122 extending into a groove 123 in the screw 119. In the end member 1, adjacent the axis of the drum 21, which at this time is in the "operative position," is a 40 control switch 124 having an actuating plunger 125. As the drum 21 is rotated, as will herein-after appear, the screw 119 is projected and finally engages the plunger 125 to actuate the switch 124. Actuation of the switch 124 controls 45 a motor circuit which prevents further unwinding of the map 22 from the drum 21.

In operating the above described device to display any selected map, the operator observes which number on the indicia bearing disk is displayed through the opening 49. As shown, the number 1 is displayed, which means that drum member 1 is in the "operative position". Supposing, for example, it is desired to display the map on the drum member 5. The operator manually 50 moves the control handle 29 and actuates the switch 26 to operate the motor 23. The switch 26 is actuated by engagement of one of the pins 31 with the radial arm 38. Operation of the motor 23 moves the chains 19, and as the indicia "4" 55 on the disk 50 passes the opening 49, the operator restores the handle 29 to its original position. When the rod 28 is rotated, say for example, clockwise in Fig. 7, the pin 31 at the left hand side of the radial arm 38 causes movement of 60 the radial arm, whereas the pin 31 at the right hand side of the radial arm 38 is retracted by engagement of its finger 34 with the adjacent cam 36. Therefore, when the rod 28 is restored to its original position, the radial arm is permitted to remain in the position to which it was 65 moved, and the switch 26 remains closed.

When the radial arm 38 was moved angularly, the arm 39 moved therewith, pulled the link 40 upwardly, and the pressure of the spring 45 caused the levers 43 and 46 to swing the cam 70

head 47 into the path of movement of the projecting elements 48 on the drums 21. While the radial arm 38 was held in its angular position, by the operator holding the handle 29, the levers 43 and 46 were rocked each time a projecting element engaged the cam head 47, such rocking merely causing compression of the spring 45. When the handle 29 was released at the passage of the fourth drum indicia, engagement of the projecting element 48 on the fifth drum with the 10 cam head 47 oscillates the shaft 44 and swings the lever 43 to pull the link 40 downwardly, thereby restoring the radial arms 38 and 39 and the switch 26 to their original positions. During this return movement the radial arm 38 strikes 15 the inclined surface 32 on the above referred to right hand pin 31, which was restored to its original position by its spring 34, and snaps to a position between the two pins 31.

At this stage in the operation, the previously 20 selected fifth drum (according to the indicia on the disk 50,) will be placed in the "operative position." The closure 14 is then swung to its open position so that access may be had to the said fifth drum. The straps 115 upon the roller 82 25 are pulled downwardly and their hook member 116 is connected to the hook member 118 on the map rolled upon the previously positioned drum.

The operator then operates the handle 172 to move the rod 68 clockwise, thus actuating the 30 switch 111 to set the motor 87 in operation and to place the pin 74 in engagement with the forked end 105 of the lever 104. Rotation of the rod 68 also rotates the collar 70, and the pin 72 acting in the spiral groove 71, rocks the lever 65 and 35 moves the splined clutch element 63 into engagement with the clutch element 100. Thereupon the foot pedal 62 is depressed and rotation of the shaft 61, caused thereby, swings the lever 99, pulls the link 98 downwardly, rocks levers 95 and 93, 40 and forces the friction disk 89 into engagement with the friction disk 83. The roller 82 is thus caused to rotate and the straps 115, in being wound around the same in their respective grooves 117, unwind the map 22 and cause it to extend 45 vertically in front of the cabinet as indicated in broken lines at A in Fig. 2. Continued rotation of the roller causes the map 22 to be wound around the same.

The maps 22 are ordinarily quite long and in 50 some cases it is desirable to move them rapidly until the portion which is to be inspected is exposed. The speed of movement of the map may be varied by pulling the rod 68 outwardly, in which case the pin 74, in engagement with the 55 lever 104 as above described, rotates the shaft 103 and swings the lever 101 to shift the motor 87 etc., whereby the point of contact between the periphery of the friction disk 89 with the surface of the friction disk 83 is moved nearer the center 60 of rotation of the latter. When such movement takes place the number of rotations of the disk 83 resulting from each rotation of the disk 89 is increased.

When the desired amount of the map has been 65 displayed its movement may be stopped by releasing the foot pedal 62 or by restoring the handle 172 to its original position where it renders the switch 111 inoperative. In order to prevent the map from being completely unwound from its 70 drum the screw 119 and the switch 124 function in the nature of a safety control, as above described.

In order to rewind the map upon the drum from which it was unwound, the handle 172 is 75

rotated counterclockwise and by rotating the rod 68 actuates the switch 111 to set the motor 55 in operation. This counterclockwise movement rotates the collar 70 and through means of the pin 5 72 and spiral groove 71 rocks the lever 65 to move the splined clutch element 63 into engagement with the clutch element 64. The pedal 62 is then depressed and through rotating the clutch elements 63 and 64 swings the flexible lever 59 and 10 causes engagement of the friction disk 53 with the friction disk 53a on the aligned drum. Rotation is thus imparted to the drum 22 and the map rewound thereupon.

Counterclockwise movement of the rod 68 15 places the pin 74 in engagement with the forked end 77 of the lever 76, and by pulling the rod 68 outwardly the shaft 75 is caused to rotate. Such rotation swings the lever 78 and shifts the bearing 57 to move the friction disk 53 nearer to the 20 center of the friction disk 53a to vary the speed of operation of the drum.

Any of the several drums 21 may be selectively placed in the "operative position" in which they are aligned with the friction disk 43 and may be 25 moved upwardly or downwardly by manipulation of the above described controls. They may also be supported in a drafting board position whereby work may be performed upon the same by placing the closure element 10 in the inclined 30 position shown at B in Fig. 2. With the closure element 10 in the inclined position B, an idler roller 126 is dropped from the elevated position shown in full lines in Fig. 2 to the position shown in dotted lines. It may be held, by its own 35 weight, in the broken line position, or any suitable securing means known to the art might be used to hold the idler roller in its lowered position.

Fig. 15 illustrates a slack take-up for the map which functions upon movement of the closure 10 40 when it is moved from the position shown in broken lines at B to the full line position shown in Fig. 2. With the roller 82 and the operative drum stationary, such movement of the closure tends to loosen the extended portion of the map. 45 This slack is taken up by rotative movement of the roller 82 relative to its supporting shaft 82a caused by a torsion spring 82b. The roller 82 is free to rotate relative to its supporting shaft 82a, and is yieldably connected thereto by the spring 50 82b. As the roller is rotated to extend a map, as above described, the spring 82b is placed under tension by the tension on the map. As the map tension is released, by lowering the closure 10, the tension of the spring rotates the roller until 55 the slack in the map is taken up.

Although a specific embodiment of the invention has been illustrated and described it will be understood that various changes may be made within the scope of the appended claims without departing from the spirit of the invention and such changes are contemplated.

What I claim is:—

1. In combination, a cabinet having a compartment for the reception of a plurality of rolls of 65 displays, movable means in said compartment supporting said rolls, said compartment having an opening through which unwound portions of said displays may be extended for inspection, means adapted to be connected to a display positioned adjacent said opening to unwind it from 70 its roll and to extend the unwound portion thereof for inspection above said compartment, means for moving said movable means to selectively place said rolls in the position adjacent said 75 opening, and means for supporting an unwound

portion of a display in a drafting board position.

2. In apparatus of the character described, a plurality of drums having displays rolled thereon, movable means rotatably supporting said drums, a housing enclosing said drums and movable means and having an opening through which an unwound portion of a display may be extended for inspection when the drum bearing said unwound display is positioned adjacent said opening, said movable means being adapted upon movement thereof to selectively position said drums adjacent said opening, means above said housing for unwinding a selected display and for extending it for inspection above said housing, and means for rewinding an unwound display 15 upon its drum, said means for unwinding said display comprising a roller having means wound about the same and adapted to be connected to a selected display whereby rotation thereof causes the unwinding display to be wound about the 20 roller, and frictional means for retarding rotation of the roller while said unwinding display is being rewound about its drum.

3. In apparatus of the character described, a plurality of drums having displays rolled thereon, 25 movable means rotatably supporting said drums, a housing enclosing said drums and movable means and having an opening through which an unwound portion of a display may be extended for inspection when the drum bearing said unwound display is positioned adjacent said opening, said movable means being adapted upon movement thereof to selectively position said drums adjacent said opening, means above said housing for unwinding a selected display and for 30 extending it for inspection above said housing, means for rewinding an unwound display upon its drum, and means for supporting an unwound portion of a display in a drafting board position.

4. In apparatus of the character described, a 40 housing having an opening therein, a rotatable support within said housing, a plurality of display supporting drums rotatably mounted on said support and adapted to be positioned adjacent said opening by rotative movement of said support, means for rotating said support, a roller positioned above said housing in spaced relation thereto, means for rotating said roller, and connecting members depending from said roller and adapted to be connected to the display on a drum 45 adjacent said opening whereby rotation of said roller unwinds the display from the drum and causes it to extend through said opening and upwardly above said housing.

5. In apparatus of the character described, a 55 housing having an opening therein, a rotatable support within said housing, a plurality of display supporting drums rotatably mounted on said support and adapted to be positioned adjacent said opening by rotative movement of said support, means for rotating said support, a roller positioned above said housing in spaced relation thereto, means for rotating said roller, connecting members depending from said roller and adapted to be connected to the display on a drum 60 adjacent said opening whereby rotation of said roller unwinds the display from the drum and causes it to extend through said opening and upwardly above said housing, and means for rotating a drum positioned adjacent said opening 65 in a direction to rewind an unwound display thereon.

6. In apparatus of the character described, a 70 housing having an opening therein, a rotatable support within said housing, a plurality of dis- 75

play supporting drums rotatably mounted on said support and adapted to be positioned adjacent said opening by rotative movement of said support, means for rotating said support, a roller 5 positioned above said housing in spaced relation thereto, means for rotating said roller, connecting members depending from said roller and adapted to be connected to the display on a drum adjacent said opening whereby rotation of 10 said roller unwinds the display from the drum and causes it to extend through said opening and upwardly above said housing, means for rotating a drum positioned adjacent said opening in a direction to rewind an unwound display 15 thereon, and friction means adapted to oppose rotation of said roller during rewinding of a display.

7. In apparatus of the character described, a housing having an opening therein, a rotatable 20 support within said housing, a plurality of display supporting drums rotatably mounted on said support and adapted to be positioned adjacent said opening by rotative movement of said support, means for rotating said support, a roller 25 positioned above said housing in spaced relation thereto, means for rotating said roller, connecting members depending from said roller and adapted to be connected to the display on a drum adjacent said opening whereby rotation of said 30 roller unwinds the display from the drum and causes it to extend through said opening and upwardly above said housing, and means for supporting an unwound portion of a display in a drafting board position.

35 8. In apparatus of the character described, a housing, a plurality of rolls of displays, a movable wall in said housing adapted to be moved to provide an opening whereby a display roll positioned adjacent thereto may be unwound and extended 40 through the opening for the purpose of inspection, means for supporting said plurality of rolls, means for moving said last named means to selectively position said rolls adjacent said opening, means for unwinding the display from a roll positioned adjacent said opening to extend the 45 same above said housing, and means for rotating a roll positioned adjacent said opening in a direction to wind a display thereon.

9. In apparatus of the character described, a 50 housing, a plurality of rolls of displays, a movable wall in said housing adapted to be moved to provide an opening whereby a display roll positioned adjacent thereto may be unwound and extended through the opening for the purpose of inspection, means for supporting said plurality of rolls, means for moving said last named means to selectively position said rolls adjacent said opening, means for unwinding the display from a roll positioned adjacent said opening to extend the 55 same above said housing, means for rotating a roll positioned adjacent said opening in a direction to wind a display thereon, and means for supporting said movable wall in an inclined position and for training an unwound portion of the 60 display thereover.

65 10. In combination, a cabinet having a housing, a drum in said housing having a map wound therearound, a roller above said housing having means thereon adapted to be connected to the 70 map on said drum whereby rotation of the roller unwinds the map from said drum, a motor adjacent said drum, a motor adjacent said roller, and independently operable clutch means between the drum and motor and the roller and motor and 75 motor respectively.

11. In combination, a cabinet having a housing, a drum in said housing having a map wound therearound, a roller above said housing having means thereon adapted to be connected to the map on said drum whereby rotation of the roller unwinds the map from said drum, a motor adjacent said drum, a motor adjacent said roller, independently operable clutch means between the drum and motor and the roller and motor respectively, and a single actuator adapted to be rendered operative to operate the different clutch means selectively. 10

12. In combination, a cabinet having a housing, a drum in said housing having a map wound therearound, a roller above said housing having 15 means thereon adapted to be connected to the map on said drum whereby rotation of the roller unwinds the map from said drum, a motor adjacent said drum, a motor adjacent said roller, and a combined variable speed drive and clutch 20 mechanism between the drum and motor and roller and motor respectively. 20

13. In combination, a cabinet having a housing, a drum in said housing having a map wound therearound, a roller above said housing having 25 means thereon adapted to be connected to the map on said drum whereby rotation of the roller unwinds the map from said drum, a motor adjacent said drum, a motor adjacent said roller, and a combined variable speed drive and clutch 30 mechanism between the drum and motor and roller and motor respectively, a single actuator for the variable speed drives and a single actuator for said clutch, said actuators being adapted to render said drives and clutches operative selectively. 35

14. In combination, a cabinet, having a compartment for the reception of a plurality of rolls of displays, movable means in said compartment supporting said rolls, said compartment having 40 an opening through which unwound portions of said displays may be extended for inspection, means adapted to be connected to the end of a display positioned adjacent said opening to unwind it from its roll and to extend the unwound 45 portion thereof above said compartment for inspection, means for moving said movable means to selectively place said rolls in the position adjacent said opening, and means for controlling the movement of said movable means, said last 50 named means being manually operable to start movement of said movable means and automatically operable to stop such movement.

15. In combination, a cabinet having a compartment for the reception of a plurality of rolls of displays, movable means in said compartment supporting said rolls, said compartment having an opening through which unwound portions of said displays may be extended for inspection, means adapted to be connected to the end of a display positioned adjacent said opening to unwind it from its roll and to extend the unwound portion thereof above said compartment for inspection, means for moving said movable means to selectively place said rolls in the position adjacent said opening, means for controlling the movement of said movable means, said last named means being manually operable to start movement of said movable means and automatically operable to stop such movement, and means 60 on said movable means for causing the automatic operation of said controlling means. 65

16. In combination, a cabinet having a compartment for the reception of a plurality of rolls of displays, movable means in said compartment 70 75

supporting said rolls, said compartment having an opening through which unwound portions of said displays may be extended for inspection, means adapted to be connected to a display positioned adjacent said opening to unwind it from its roll and to extend the unwound portion thereof for inspection above said compartment, means for moving said movable means to selectively place said rolls in the position adjacent said opening, means in said compartment for rewinding an unrolled display, manual means for operating said movable means for positioning a selected display adjacent said opening and in an operative position with respect to said rewinding means, and automatic means for stopping said movable means when said selected roll is in said operative position.

17. In combination, a cabinet having a compartment for the reception of a plurality of rolls of displays, movable means in said compartment

supporting said rolls, said compartment having an opening through which unwound portions of said displays may be extended for inspection, means adapted to be connected to a display positioned adjacent said opening to unwind it from its roll and to extend the unwound portion thereof for inspection above said compartment, means for moving said movable means to selectively place said rolls in the position adjacent said opening, means in said compartment for rewinding an unrolled display, manual means for operating said movable means for positioning a selected display adjacent said opening and in an operative position with respect to said rewinding means, means for indicating the position of the selected roll with respect to said operative position, and automatic means for stopping said movable means when said selected roll is in said operative position.

MYRON D. McCUALEY. 20
